The ornamental design for a ski carrying handle, as shown and described.

DESCRIPTION

FIG. 1 is a front elevational view of a ski carrying handle showing our new design with the rope loops in position to support spaced portion of skis, the rear elevational view being a mirror image thereof;

FIG. 2 is a top plan view of the ski carrying handle with the rope assembly omitted for convenience of illustration;

FIG. 3 is a bottom plan view thereof;

FIG. 4 is a cross-sectional view taken along line 4—4 of FIG. 2;

FIG. 5 is an end elevational view of FIG. 2;

FIG. 6 is an enlarged scale cross-sectional view taken along line 6—6 of FIG. 4; and

FIG. 7 is an enlarged scale cross-sectional view taken along line 7—7 of FIG. 4.
